UNITED STATES PATENT OFFICE.

HECTOR ANDREINO, OF LE LOCLE, SWITZERLAND, ASSIGNOR TO SOCIETY FABRIQUES DES MOUTRES ZENITH SUCCESEUR DE FABRIQUES DES MOUTRES ZENITH GEORGES FAVRE-TACOT & CIE, OF LE LOCLE, SWITZERLAND.

MAGNETO.

Application filed December 9, 1920. Serial No. 429,515.

To all whom it may concern:

Be it known that I, HECTOR ANDREINO, a citizen of the Swiss Republic, and resident of Le Locle, Switzerland, have invented new and useful Improvements in Magnetos, of which the following is a full, clear, and exact specification.

The present invention relates to magnetos for internal combustion engines of the kind comprising a U-shaped magnet of the usual form, a fixed induction coil, and a rotary flux distributor having two flux conducting segments located in the space between the pole pieces of the magnet. The magneto of the present invention differs from other known magnetos of the kind above specified in that, the axis of rotation of the flux distributor being parallel to the arms of the magnet, the induction coil is carried by a core forming part of a magnetic yoke surrounding the pole piece end of one of the arms of the magnet, and arranged in the same transverse plane perpendicular to the axis of rotation as the pole pieces of the magnet and the segments of the flux distributor. The flux distributor is so arranged that during its rotation a path for the magnetic flux of the magnet is completed in known manner through the yoke by the flux distributor alternately in one direction and the other. The flux distributor and the magnetic yoke are arranged by the construction adopted to be conveniently laminated in the same plane perpendicular to the arms of the magnet and to the axis of rotation of the flux distributor, with the object of reducing to a minimum the reluctance of this part of the magnetic circuit, and of favorably influencing the operation of the magneto. The particular arrangement of the induction coil carrying yoke allows also to easily engage the same over the magnet end.

The invention is illustrated in the accompanying drawing of which—

45 Figure 1 is a view in sectional end elevation, and

Figure 2 is a view in sectional side elevation of one constructional form of magneto embodying the invention.

50 Figures 3 and 4 are detail sectional views illustrating different constructional forms of magnet which may be employed.

Referring now first to Figures 1 and 2, the stationary U-shaped permanent magnet of

the magneto is indicated at 1, the arms of 55 which in the normal position of the magneto are horizontal and arranged one above the other, being provided with laminated pole pieces 5 surrounding the free ends of the arms of the magnet as shown. In the cylindrical space between the pole pieces 5 are located the laminated segments 2 of the flux distributor which are mounted upon a non-magnetic support 3 carried by end shafts 4 which are rotatably mounted in ball bearings 60 (not shown). The support 3 carrying the segments 2 and the end shafts 4 constitute the rotary flux distributor the axis of rotation of which is parallel to the arms of the magnet 1. A fixed induction coil 6 is provided which surrounds a core 7 forming part of a laminated yoke located in a plane perpendicular to the axis of rotation of the flux distributor, the two arms 8 of the yoke surrounding the upper arm of the magnet 1, 75 and terminating in pole pieces 9, displaced at an angle of 90° relatively to the pole pieces 5 of the magnet. The whole structure above described is enclosed in a protective casing or cover 10 which also accommodates 80 the other usual magneto mechanism, such as the contact breaker, current distributor etc. not shown on the drawing.

By the rotation of the flux distributor 2, 3, 4 a path for the magnetic flux from the 85 magnet 1 is completed through the yoke 7, 8, 9, by the segments 2 in one and the other direction alternately, and there are thus produced in the yoke 7 four reversals of flux direction for each revolution of the distributor 90 2, 3, 4.

The relative arrangement of the various elements above described permits the pole pieces 5, the segments 2, and the yoke 9, 8, 7 to be conveniently laminated in the same 95 plane perpendicular to the arms of the magnet and to the axis of rotation of the flux distributor. This lamination enables the reluctance of the magnetic circuit to be reduced to a minimum and favorably influences the operation of the magneto.

In the construction shown in Figures 1 and 2, the permanent magnet 1 is formed in a single piece. The magnet may however, also be made in several U-shaped sections arranged laterally or vertically relative to one another as shown in the modified constructions of Figures 3 and 4 respectively.

The pole pieces 5 may also, in order more or less easily to collect the flux from the arms of the magnet 1, surround these arms on three sides, (as shown in Figures 1 and 5 2) or on all four sides (as shown in Figure 3) or completely on three sides and partially on the fourth side (as shown in Figure 4).

In these and other respects the constructions above described may obviously be modified without exceeding the scope of the invention.

What I claim is:

A magneto for internal combustion engines, comprising a stationary U-shaped permanent magnet with opposite pole pieces and a rotary flux distributor located between the pole pieces of said magnet, having its axis of rotation parallel to the longitudinal axis of said magnet and being provided with flux 15 conducting segments for completing during rotation a path for the magnetic flux of the

magnet, in combination with an induction coil carrying magnetic yoke engaged round the pole piece end of one of the arms of said magnet so as to be in the same transverse 25 plane perpendicular to the axis of rotation as the magnet pole pieces and the flux distributor segments, the pole pieces of the permanent magnet, the segments of the flux distributor and the yoke being laminated in 30 the said plane perpendicularly to the arms of the magnet and to the axis of rotation of the flux distributor, substantially as and for the purpose described.

In witness whereof I have hereunto signed 35 my name this 17th day of November, 1920, in the presence of two subscribing witnesses.

HECTOR ANDREINO.
